(57) **CLAIM**

The ornamental design for a dual-arm retention sling, as shown and described.

DESCRIPTION

FIG. 1 is a front, left-side, top perspective view of the dual-arm retention sling in use, showing the new design; FIG. 2 is a front, top perspective view thereof; FIG. 3 is a front elevational view thereof; FIG. 4 is a rear elevational view thereof; FIG. 5 is a right-side elevational view thereof; FIG. 6 is a top plan view thereof; FIG. 7 is a front elevational view thereof, in use; FIG. 8 is a rear elevational view thereof, in use; FIG. 9 is a left-side elevational view thereof, in use; FIG. 10 is a right-side elevational view thereof, in use; and, FIG. 11 is a top plan view thereof, in use. The broken lines depict environment and form no part of the claimed design.
